ABSTRACT: A method and apparatus are disclosed for improving the efficiency of processing and storing algebraic and similar information in a data processor. Polynomial information is treated as an array of coefficient and exponent information subject to machine boundary conditions, user format statements and linking signals. Dynamic storage allocation and exponent overflow are also provided.

FIG. 5E-2

MACHINE PROCESSING OF ALGEBRAIC INFORMATION

This invention relates to the processing of information by machine and more particularly to the processing of algebraic information.

In a general sense information can be represented by sequences of characters which are said to constitute symbolic strings. The individual characters may be numeric, alphabetic, or they may be arbitrary symbols. As a preliminary to processing they are converted into code signals and stored.

In the case of algebraic information a symbolic string is constituted of expressions whose terms are linked by operation symbols. Each term includes integral coefficients, variables, and exponents.

In pristine form a representative algebraic expression is $3X^2Y+Z$. The first term $3X^2Y$ has an explicit coefficient of 3, a variable X with an explicit exponent of 2, and a variable Y with an implicit exponent of unity. The second term Z is linked to the first by the explicit operation symbol +. In addition to the implicit operation of exponentiation, the first term also contains an implicit operation of multiplication.

For data processing purposes all operations must be explicit. In keeping with this requirement one well-known convention uses a single asterisk to represent multiplication and a double asterisk to represent exponentiation.

According to this convention the foregoing example becomes $3*X**2*Y**1+1*Z**1$ and includes the explicit representation of implicit exponents and coefficients.

In order to be converted into machine terms each individual character of a symbolic string, such as that representing the foregoing algebraic expression, is converted into a preassigned set of code signals. According to one well-known convention, six binary code signals are required for each character. Since each set of three binary signals can be represented by an octal number, two such numbers are used for each character and the foregoing expression, with all operations explicit, takes the form

03 54 67 54 54 02 54 70 54
54 01 20 01 54 71 54 54 01

which has the binary form

000011 101100 110111
101100 101100 000010
101100 111000 101100
101100 000001 010000
000001 101100 111001
101100 101100 000001

Thus the representation of the foregoing algebraic expression in machine terms can require up to 108 binary signals. For more complicated expressions the number of required symbols increases correspondingly. It is apparent for even relatively simple algebraic manipulations the storage capacity of even a large-scale machine can easily be exceeded.

Accordingly it is an object of the invention to reduce the number of symbols required in the representation of algebraic information. A related object is to reduce the amount of storage required.

When algebraic information is manipulated as an extended string of characters with preassigned symbols representing variable names and operations, including arithmetic operations and exponentiation, not only is extensive storage required, but it also becomes necessary to scan and identify the various symbols in order to determine the nature of the operation to be accomplished and to identify the associated data. Such operations are time consuming. They require the analysis of extended strings with the result that the processing machine must either have extremely large-capacity registers or it must scan data over many cycles before an operation can be completed.

Accordingly it is a further object of the invention to reduce the amount of time required in the processing of algebraic information. Still another object is to permit the manipulation of algebraic information with associated processing components of modest capacity.

In accomplishing the foregoing and related objects, the invention provides for representing algebraic expressions by their coefficients and exponents only. The position of the exponent indicates the variable with which it is associated.

- 5 For the algebraic expression $3X^2Y+Z$ considered earlier, the first term is represented by the coefficient 3 and the exponent set 210, the first two digits of the exponent set indicating the respective powers of the first and second variables X and Y, and the remaining digit indicating that the variable Z, which is absent from the first term, is raised to the zero power. Similarly the second term is represented as 1,001.

In signal terms the coefficient and exponent of each term occupy one or more machine words. Typically the coefficient is separated from the exponents which are packed, depending upon size, into one or more machine words.

- 20 upon size, into one or more machine words.
Besides coefficient and exponent signals, format signals are generated which indicate the names of the variables and the maximum sizes of their exponents. The format signals also include a mask for checking certain arithmetic operations such as multiplication and indicating the way in which the exponent signals are packed. In multiplication, for example, the exponent signals must be added without overflow from one packing position to another. For the illustrative expression, the exponent set 210 of the first term can be added to the exponent set 001 of the second term without danger of a carry from one digit position to another. Verification that there has been no overflow, i.e., carry, is made using the mask.

As a result of the polynomial representation prescribed by the invention, there is a saving in time that would be otherwise required in the scanning of operation symbols. In addition, the elimination of symbols for representing variables and for indicating exponentiation reduces the required amount of machine storage. In a mathematical sense the invention provides for representing each term of an algebraic expression as a coefficient and a set, i.e., vector, of exponents.

To facilitate the processing of algebraic information, the invention provides for the lexicographic ordering of exponent sets that have been entered into storage. The designation lex-

- 40 icographic means that the exponent sets are ordered in a fashion similar to the ordering of words in a dictionary except with letters replaced by numbers. For the purpose of lexicographic ordering each exponent set is treated as ordinary numbers which are then sorted in numerical sequence. In the earlier example, the exponent set represented by 210 would follow the exponent set represented by 001 at the conclusion of the sorting process. Thus each polynomial entered into storage becomes an ordered vector of exponent sets with each set accompanied by its appropriate coefficient.

- 50 In the processing of polynomial information, the invention provides for initialization, followed by input, arithmetic and output manipulations. Initialization includes the establishment of format and polynomial reference locations in machine memory and the allocation of adequate data storage, the latter constituting a data buffer. Reference locations are also provided for the inner and outer bounds of the data buffer. The outer bounds are fixed, but the inner bounds are variable. As long as the data buffer is empty, the inner and outer bounds coincide.

- g 60 Input begins with format information, which, for each variable, represents the name of the variable, followed by an indication of its maximum exponent size. This information is stored beginning at the format reference location and is used in generating mask signals.

- 65 The format input is followed by polynomial data. For each polynomial, a heading that is accessible from an associated reference location is created in the lower portion of the data buffer. The heading includes (1) the beginning address of the coefficient and exponent signals which are stored in the upper portion of the data buffer, (2) the address of the format reference location, and (3) the number of terms in the polynomial.

Each coefficient typically occupies a machine word and is followed by one or more words of exponent sets which are packed in accordance with format requirements.

As the data buffer becomes occupied, updating adjustments are made in the variable inner bounds in order to indicate the next available locations in the upper and lower portions of the data buffer.

The coefficient and exponent words entered into the data buffer may be initially in the lexicographic order described earlier, in which case the polynomial is said to be in "canonical" form. However if it is not, it is so ordered.

Once the format and polynomial information have been stored, a variety of polynomial arithmetic manipulations can be undertaken. One such illustrative operation is the multiplication of one polynomial by another. This proceeds by one of two methods. If there is sufficient available space in the data buffer, a "leapfrog" technique is used. Otherwise a slower "compact" method is used. In the leapfrog method, space is reserved in the data buffer for blocks of storage amounting to one plus the number of terms in the smaller polynomial and each capable of accommodating all of the terms of the larger polynomial. Then the smaller polynomial is treated monomially, i.e., a term at a time, to multiply all of the terms of the remaining polynomial. Each such multiplication produces a partial product which is stored at one of the blocks. The first two partial products are combined into a partial sum which is stored at the beginning of a new block and allowed to overwrite one of the earlier blocks, if necessary. Each partial sum is combined with a subsequent partial product. This procedure is repeated until the desired result appears at the beginning of the first reserved block.

Using the compact method of multiplication, storage is required only for the longest partial sum and the terms of the longer polynomial. The last partial sum starts at the top of the available storage. The next partial product is placed immediately below it and then both are moved down, leaving a gap that is of the same extent as the number of terms in the longer polynomial. A partial product is then added to the partial sum to produce a new partial sum starting at the top of the available space and overwriting, if necessary, a portion of the previous partial sum.

As a result of the canonical form prescribed by the invention, operated in conjunction with the polynomial format, there is an enhancement in the speed of the operation and simplification of term by term processing.

Contributing to the speed of operation is the packing of selected machine words with pluralities of distinctive items, such as the exponents of a set. This permits the items, e.g., the exponents, to be processed on a word-by-word basis instead of individually. For such words, each item occupies a distinctive region. As long as the regions remain distinctive, there is no error. However, if an overflow takes place from one region to another, the operation has to be rejected.

To indicate the occurrence of any overflow, the invention provides mask signals which delimit the various regions. Each word resulting from an operational sequence being tested is subjected to the equivalent of an Exclusive-OR operation with its source words. This procedure eliminates all noncarry signals from the word under test which is then subjected to an AND operation with the mask signals. If there had been no carry into the mask position, the result would have been zero; nonzero otherwise.

The final manipulation is the extraction of the processed data signals from storage. This can be done by adopting well-known output techniques commonly employed with data processing machines.

Other aspects of the invention will become apparent after considering an illustrative embodiment in conjunction with the figures in which:

FIG. 1A is a listing of a representative main program in accordance with the invention;

FIG. 1B is a diagram of memory storage allocations during assembly;

FIGS. 1C-1 through 1C-3 are diagrams of memory storage allocations during execution;

FIG. 2A is a listing of a macrodefinition corresponding to the first instruction of FIG. 1A;

FIG. 2B is a calling sequence for the subroutine corresponding to the first instruction of FIG. 1A;

FIG. 2C is a listing of the subroutine corresponding to the first instruction of FIG. 1A;

FIG. 3A is a listing of a macrodefinition corresponding to the second instruction of FIG. 1A;

FIG. 3B is a flow chart for the subroutine corresponding to the second instruction of FIG. 1A;

FIG. 3C is a flow chart expansion of the last set of operations included in the flow chart of FIG. 3B;

FIG. 3D is a diagram of memory storage allocated in the vicinity of the format statement of FIG. 1C, showing assignments made to the format statement by the subroutine of FIG. 3B;

FIG. 4A is a listing of a macrodefinition corresponding to the third instruction of FIG. 1A;

FIGS. 4B-1 and 4B-2 are flow charts for the subroutine corresponding to the third instruction of FIG. 1A;

FIG. 4C is a diagram of memory storage allocated in the vicinity of the stored main program, the stored subroutine of FIG. 2C, and the data buffer of FIG. 1C, showing assignments made by the subroutine of FIG. 4B;

FIGS. 4D-1 and 4D-2 are flow charts for the canonical form subroutine included within the flow chart of FIG. 4B;

FIG. 5A is a listing of a macrodefinition corresponding to the fourth instruction of FIG. 1A;

FIG. 5B is a diagram of data buffer storage illustrating "leapfrog" polynomial multiplication;

FIG. 5C is an overall flow chart for the subroutine corresponding to the fourth instruction of FIG. 1A;

FIGS. 5D-1 through 5D-3 are expanded flow charts of the flow chart of FIG. 5C; and

FIGS. 5E-1 and 5E-2 are respectively a listing and a block diagram for checking exponent addition in accordance with the invention.

The method of processing information by the embodiment here disclosed is independent of the machine by which it is performed. It is only necessary that the machine have a memory unit for storing signals representing information, a unit for entering signals into and extracting them from storage and units for manipulating and decoding the signals.

For the sake of illustration, the method is specified in terms of operations which are used with machines of the IBM 700 series. One well known machine of this series is the IBM 7090

which is described in IBM Form 223-6895-2 dated June, 1962, entitled IBM 7090 Data Processing System. The central constituent of the IBM machine is a memory unit, known as

core storage, for the semipermanent storage of information in magnetic cores. The contents of core storage are gated into and out of various registers, which are used for the temporary storage.

One of the registers of the IBM machine, the address register, specifies the location in core storage of the current information item, whether it be an instruction or a data item. The address register is controlled in part by an instruction location counter. Address modification and auxiliary counting operations are performed with a set of index registers. Logical operations are performed by a so-called sense indicator register.

There are two registers in the IBM machine for arithmetic operations. The first is a so-called accumulator which operates in conjunction with an adder for registering the cumulative results of operations which yield the equivalent of addition and subtraction. The other arithmetic register is a so-called multiplier-quotient register which is used in conjunction with the accumulator to perform multiplication and division.

With such a machine, operational sequences are communicated through the medium of punched cards or their equivalent, such as magnetic tape. Typically, each card contains an "instruction" which includes an operation portion. A set of cards contains instructions which form a "program" and constitute a source deck.

In processing algebraic information in accordance with the invention, symbolic specification is made in terms of a source language which is translated into machine language by a compiler.

The operations of FIG. 1A translated by the compiler include (1) the reservation of a block of storage for data at the time of assembly and the initialization of storage allocation at the time of execution; (2) the storage of polynomial format information; (3) the storage of polynomial information according to the format statement. This operation includes the designation of a set of storage locations which include the address of the polynomial, the address of the format statement and the number of terms in the polynomial statement. This operation also provides for the dynamic allocation of storage and the sorting of the polynomial terms into canonical form; (4) the performance of a designated polynomial operation, for example, the multiplication of two polynomials and (5) the extraction from storage of the results of step 4.

The compiler includes macrodefinitions. These allow the user to specify the ultimate operations of the machine in terms of his own choosing. For example, no existing information-processing machine includes a basic machine operation by which two polynomials can be added together. However, using the macro-operation, the user can specify such an operation, such as POLMPY, for Polynomial Multiply. In an elementary compiler, the macros essentially contain calls to subroutines and the calling sequence of those subroutines. In advanced versions, the compiler is used for such varied tasks as defining other macros and providing flexibility to the manipulation of polynomial quantities.

A representative specification of operations for the multiplication of two polynomials P and Q is set forth in FIG. 1A. The listing of FIG. 1A constitutes a "main program." Each line of the listing is composed of characters entered on one card of the source deck. For ease of reference the entries of FIG. 1A are numbered sequentially from 10-1 through 10-11.

As shown, disregarding the reference numbers which have been supplied for identification only, each line of FIG. 1A contains distinctive fields of contiguous characters, respectively designated from left to right as the location, operation and variable fields.

The operation field contains the symbolic counterpart of signals which, in the listing of FIG. 1A, are calls to macro instructions. POLBEG at reference No. 10-1 names the polynomial operations by which storage is allocated for the data to be processed. POLRDF at reference No. 10-2 names the operations for Reading the Polynomial Format Statement. POLRDD at reference Nos. 10-3 and 10-4 names the operations for reading the polynomials P and Q, respectively. POLMPY at reference No. 10-5 names the operations for multiplying two polynomials together. POLPRT at reference No. 10-6 names the operations for printing the resulting polynomial R.

The terminal entries FORMAT, P, Q and R, at reference Nos. 10-8 through 10-11 of FIG. 1A are in the location field of the listing. The first of these entries, symbolized by FORMAT, provides storage positions of the format statement read by POLRDF. It is preceded by reference No. 10-7 which explicitly specifies the number of format storage locations as being 20. The remaining entries P, Q and R have blank operation fields. They constitute pointers to data storage locations. Their operand, or variable, fields are supplied with pointer signals during data processing. Such signals are supplied at location P by POLRDD P, FORMAT; at location Q by POLRDD Q, FORMAT; and at location R by POLMPY, R, P, Q.

Initially, the main program of FIG. 1A is assembled to bring about the conversion of the various operation codes into various storage allocations and calling sequences which are discussed in greater detail subsequently.

In bringing about the first assembly, the memory of the machine is manually loaded with a system program which is used in loading other listings and in monitoring the progress of

data processing. A suitable system program is BE-SYS-3, for Bell System Program, Version 3, which is available generally through the users' organization of IBM 700 machines known as SHARE. As shown in FIG. 1B, BE-SYS-3 occupies the first 100₈ locations in memory as well as locations 60000₈ through 77777₈. The subscript 8 indicates that the companion numbers are to the base eight, or octal, according to the well-known convention for designating locations in a binary machine in terms of a power of 2. Octal numbers are commonly written without commas. The corresponding decimal locations are 64₁₀ and 24,576₁₀ through 32,767₁₀.

This division of the system program into two sections stems from the desirability of having the loading section in the early portion of the memory while allowing the monitoring section to appear near the end of the memory.

Once the system program is loaded, it is used, in turn, to load the compiler and an assembly program, by which symbolic operation codes of the main program are translated into machine-code binary signals. A suitable assembly program is BE FAP which is in the widely used FAP, for Fortran Assembly Program, language. BE FAP is supplied as an adjunct to BE SYS 3. The name FORTRAN is of historical significance only.

The operational portion of the FAP assembler occupies octal locations 101 through 17132. In addition, the assembler includes three sets of tables. One of these is designated the combined operations table and contains the BCI counterparts along with the code signal forms of the basic machine operations. A second table, designated the macro table, is used in storing the definitional items of each macro-operation. A third table, designated the symbol table, is reserved for strings, known as symbols, of one or more nonoperational characters that appear in the main program listing. For example, in FIG. 1A, such strings are FORMAT R, P and Q in the location field. During assembly, the location counter is advanced one unit at a time for each machine instruction encountered, except in the case of storage allocation instructions. When a symbol is encountered, such as FORMAT R, P or Q, the binary-coded counterpart of that symbol is entered into the symbol table together with the value of the instruction counter at the point where the symbol was encountered.

In the initial assembly of the main program, a deck of cards containing the various macrodefinitions applicable to the listing of FIG. 1A and a further deck containing the information of the listing in FIG. 1A are applied to the machine. In addition, the decks are preceded by a FAP control card, which is used to initiate loading by the system program and also to call the FAP assembler. During assembly, the cards are read one at a time. The contents of the macrodefinitional cards of the compiler are entered into the macrotable of the assembler. When the cards corresponding with the program listing in FIG. 1A are encountered, their operation fields are seen to contain operation codes which do not represent standard FAP operations. However, when macros are entered into the macrotable, their names are added also so that a reference to the table for any particular macroname produces in turn a reference to the constituents of that macro. Where the operation code does not represent a macro, or is for some other reason not entered into the combined operations table, the assembler produces an error indication to that effect. The various macrodefinitions are subsequently treated by the assembler as if their constituent instructions had been originally included in the listing of the main program. The assembly requires two passes. During the first pass, the symbol table is formed and equivalents, indicated by the location counter, are assigned to the symbols. During the second pass, the symbols of the operand field are evaluated using the symbol table and the operation fields are converted to machine code using the combined operations table. At the conclusion of the second pass, the output tape contains the assembled main program.

Subsequently, the assembled main program is loaded into the machine, with the results shown in FIG. 1C, to bring about the desired data processing. As before, the machine includes

the monitor program. However, the main program appears in place of the assembly program. In addition, the subroutines that are called by the main program are also entered into storage and bear the designation ALPAK, for Algebraic Package.

The first macrodefinition POLBEG of the compiler is set forth in FIG. 2A. This macro-operation serves two functions: it provides a calling sequence to the subroutine of FIG. 2B and, in addition, it establishes the data buffer shown in the machine storage map of FIG. 1C.

The signals corresponding to the operation fields of FIG. 2A are active only during assembly, and hence are called assembly operations. They draw upon machine operation subroutines which are a part of BEFAP.

The macro-operation at reference No. 20-1 causes the symbolic coding included between reference No. 20-2 and the END operation at reference No. 20-5 to be entered into the macrotable of the assembler (FIG. 1B). When the POLBEG macro is called during the assembly of the POLBEG instruction of FIG. 1A, the CALL assembly operation at reference No. 20-2 is translated into a calling sequence for the POLBEG subroutine taking the form shown in FIG. 2B. In addition, the CALL operation places the binary-coded informational counterpart of the subroutine name at the head of the assembled main program in a so-called "transfer vector" as shown in FIG. 1C and with an effect discussed subsequently.

The COMMON assembly operation at reference No. 20-3 of FIG. 2A reserves a section of the machine memory known as common storage. This storage is established with respect to the last available location of machine memory. As shown in FIG. 1C the common storage begins at location 57777₈ before the block of memory assigned to the monitor program, beginning at location 60000₈. The designated memory allocation in the common portion of machine memory is made by adjusting the location counter assigned for this purpose. As seen from FIG. 1C, the memory storage allocations can be made downward with reference to the beginning of storage at location 101, or upward with reference to the end of storage at location 60000. Two so-called location counters, which are specified memory locations within the monitor program, are used for this purpose.

The COMMON assembly operation alters the stored contents of the location assigned to the common counter by the size of the argument in the operand field, which for the listing of FIG. 2A is given as SIZE-1. However, the argument used during assembly is an absolute expression, i.e., a number which indicates the amount of storage being allocated to the data buffer. Initially, the common "counter" contains the signals representing the number 57777₈. If SIZE is 1,000 decimal, the octal counterpart of SIZE-1 is 1,747, so that the COMMON operation at reference No. 20-3 changes the common counter from 57777 to 56030.

The next COMMON operation at reference No. 20-4 of FIG. 2A reduces the common counter by one to 56027. The symbol CR1 in the location field of reference No. 20-4 is "created" during the assembly of the POLBEG macro. It is assigned a regular storage allocation during the assembly of the main program.

At the time the main program is executed, the POLBEG instruction of FIG. 1A, as assembled according to FIG. 2B, produces a transfer to the POLBEG subroutine of FIG. 2C, as indicated by the arrows in FIG. 1C. This is accomplished through the instruction at reference No. 21-1 of the calling sequence, TSX, for Transfer and Set the designated index register IR. When the assembled main program is loaded into the machine, the binary-coded representation of the subroutine name in the transfer vector is replaced by the loading location of the corresponding subroutine. Thus, at execution time, the TSX command in the main program produces a transfer to the transfer vector location which, in turn, produces a transfer to the first instruction of the associated subroutine, as indicated by the arrows in FIG. 1C.

The other instructions at reference Nos. 21-2 and 21-3 in the calling sequence of FIG. 2B supply arguments to the POLBEG subroutine in the manner discussed subsequently. The command PZE for Plus Zero is represented, in its operation, by signals which do not produce a decoder output. Consequently, the signals in its address portion can be used to store information for the subroutine.

In addition to indicating a transfer to the subroutine, the TSX instruction of the calling sequence provides for storing signals indicating the 2's complement of the present setting of the instruction location counter in the specified index register IR. In the IBM 7090 this index register is typically the fourth. When the stored contents of IR 4 are supplemented by one plus the length of the calling sequence, the register indicates the position of the main program to which a return is to be made upon completion of the subroutine.

As for the POLBEG subroutine of FIG. 2C, its first instruction at reference No. 22-1 causes the machine signals representing the beginning location of the data buffer to be entered into the accumulator. This is brought about through the effect of operand field 2, 4. The instruction CLA, for Clear and Add, causes the accumulator to be set to zero, followed by signals from the memory location indicated by the first subfield of the operand field as modified by the contents of index register No. 4. The net result is that the contents of the memory location associated with reference No. 21-3 of the assembled calling sequence of FIG. 2B are entered into the accumulator. This is the beginning location of the data buffer. The instruction at reference No. 22-2 next causes the beginning location of the data buffer to be stored at the internal memory location A at reference No. 22-8 of the POLBEG subroutine, as shown in FIG. 1C. The A location contains a so-called pointer to the beginning point of the data buffer. In addition, there is a B pointer which initially contains the same designation as the A pointer but is adjusted downward, i.e., increasing in size as the data buffer is occupied.

The next task of the POLBEG subroutine is to indicate the terminal position of the data buffer. This is done by the instruction at reference No. 22-4 of FIG. 2C by which the second item of the calling sequence is added to the beginning location of the data buffer. The terminal location of the data buffer is stored at internal locations C and D of reference Nos. 22-10 and 22-11 by the instructions at reference Nos. 22-5 and 22-6. As with the A and B pointers, the C and D pointers are initially at the same position. During processing, the C pointer is moved upwards, i.e., decreasing in size. The final instruction of the POLBEG subroutine at reference No. 22-7 causes a return to the main program.

The second command of FIG. 1A, POLRDF, produces a call to an associated subroutine, by the macro set forth in FIG. 3A, in a fashion similar to that of the POLBEG command considered earlier. The processing operations accomplished by the POLRDF subroutine are summarized in the flow chart of FIG. 3B. The reference numbers included in the flow chart identify the detailed coding of the subroutine included in Appendix I.

The detailed coding of Appendix I is in two sections. The right-hand section forms a listing similar to those of FIGS. 1A and 2A through 2C. The left-hand section represents the actual machine signals corresponding to the coding of the right-hand section.

In essence the POLRDF subroutine transfers input format information to the region of the memory assigned to the format statement of the main program as shown in FIG. 1C. In addition, the input format information generates mask signals which are used in polynomial multiplication to prevent exponent overflow in a manner considered subsequently.

As applied at the input the format information is an alternating sequence of variable names and field widths separated by commas. In the case of polynomial information with three variables X, Y and Z, a representative sequence is

in which the field width integer following each variable name is translatable into the maximum exponent size of the associated variable. For example, in a binary machine, the field number 6, following the variable X indicates that the exponent of the variable X cannot exceed 63 or 2^6-1 bits per machine word. The sum of the field widths indicating exponent sizes is 36 which is the same as the number of bits in each word of the IBM machine used in the illustrative processing, so that only a single exponent word of machine storage is required. However, there is no restriction on the number of exponent words and more than one such word can be specified in the format statement and generated from it.

Although in the particular example being considered each variable name consists of but a single alphabetical character, it is to be understood that the variables may be specified by strings of characters. In the case of the IBM 7090 computer operated in conjunction with the BEFAP assembler each variable name may consist of a string of up to six characters.

Returning to the flow chart of FIG. 3B, the enclosures that figure summarize the results of the individual operations shown in the detailed listing of Appendix I. The boxes are of two kinds: Rectangular, indicating collections of operations and diamond, indicating decisional processes. It is to be understood that a decisional process may be included among a collection of operations.

The first set of operations (506-515) summarized by the flow chart of FIG. 3B initializes internal storage locations of the POLRDF subroutine. The initialized locations, selectively represented in FIG. 1C, fall into one of two categories. They are either internal "counting" locations or they identify locations of the format statement. For example, the location designated V is used to count the number of variables that have been processed. On the other hand, the location designated LV makes reference to the second word format statement, which contains the maximum number of variables in a polynomial. (693-695 and 699-706).

In addition to the counting and format locations, the internal storage locations include an internal data buffer which constitutes a block for temporarily holding the format information as it is read. The only requirement on the internal data buffer is that it be large enough to contain all the information read from each card. (697-698).

Once the subroutine is initialized, the binary-coded data contained on the card is read into the internal buffer. (516-521). The reading takes place through the use of a standard system subroutine.

Next, three index registers are initialized to monitor the completion of the format statement. (522-528). The first index register, known as IR1, is used to indicate the next word that is to be extracted from the internal data buffer. It is initially set to the beginning location A of the internal buffer and is incremented each time that a word is extracted. The second index register, known as IR2, gives the number of characters remaining in each word extracted from the internal data buffer and is, in the case of the IBM 7090, initially set with the count of six. The third index register, IR4, gives a count of characters in the name of each variable. At the beginning of processing, the count is one and increases by one each time a new character constituent of a variable name is encountered.

After the index registers are set, the first word from the internal data buffer is entered into the multiplier-quotient register and a first six-bit character is shifted into the accumulator. (529-533). Additional characters enter the accumulator until the variable name is complete. Following testing, the signals of the variable name are stored at the appropriate format address. (529-565).

If the variable name occupies the entire internal data buffer, it is necessary to replenish the buffer by reading data from another card (566-575). In any case, because of the way in which the format statement is constituted, a number indicating the number of bits in the variable should follow it. Initially a test is made to verify that the next character is an integer, followed by a test to determine the number of integers con-

stituting the exponent size. (576-580 and 595). For the example under consideration the exponent size is limited to two integers. Consequently the integer-processing routines provide for multiplying the first integer by 10 (583-587). If there is a second integer, it is added to 10 times the product of the first and stored in the format statement; otherwise the first digit alone is stored. (598-599 and 606-608).

The next character following an exponent length indication may be a blank, in which case the format information from the input has been completed. Otherwise a return is made to the beginning of the character processing routine and the earlier procedure repeated until a blank is encountered following a number field in the format information. (623-648).

By the time a terminal blank is encountered, the format statement contains alternate entries giving the binary-coded counterparts of the variable names as shown in FIG. 3D. For the example under consideration the variables are represented as

$$\begin{aligned} X &= 67_8 = 110111_2 \\ Y &= 70_8 = 111000_2 \\ Z &= 71_8 = 111001_2 \end{aligned}$$

Following each variable name is an indication of the maximum number of bits permitted in the associated exponent which, for the example, is

$$\begin{aligned} B_1 &= B_X = 18_{10} = 22_8 \\ B_2 &= B_Y = 12_{10} = 14_8 \\ B_3 &= B_Z = 6_{10} = 6_8 \end{aligned}$$

Once a terminal blank is encountered, the first two words of the format statement are filled in to specify the number of exponent words and the number of variables. (656-683). For the example under consideration the number of exponent words is unity and the number of variables is three, which information is entered into the first two words of the format accordingly as shown in FIG. 3D.

The final task of the POLRDF subroutine is to generate the format mask. In effect the mask is constituted by placing "1" bits to demarcate the exponent subwords. Thus, in the example under consideration, the number of bits assigned to the variables X, Y, Z are 18, 12, 6, respectively, and a "1" bit is placed at the 18th, 30th, and 36th bit positions accordingly to form the mask word 000001000101 shown at the end of the format statement of FIG. 3D. A detailed flow chart for the construction of the mask is given in FIG. 3C.

The construction of the mask begins by setting IR1 (Index Register 1) with an indication of double the number of variables included in the format statement. (656-657). Next, addresses are generated from which the format locations in FIG. 3D of the bit sizes for the M-th and the M+1st variables can be determined with respect to the index register. (658-662). In the example being considered, the generated addresses are respectively the mask address +1 and the mask address +3. The mask address is, in turn, equal to the format address + double the number of variables +2. Thus the locations given by the generated addresses with respect to the initial contents of the index register are the respective locations of the bit sizes B_1 and B_2 for the first and second variables.

After the mask location of the format statement has been zeroed, as well as an internal location NB for totaling the exponent bits, a "1" is entered into the right-hand mask position of the format statement. (663-667). The bit size of the M-th variable is added to the total at location NB. (668-670). If the total is less than 36, the mask is incomplete and the right-hand "1" is shifted to the left according to the number of bits indicated for the M+1st variable. (671-677). The contents of the index register are next decremented and the foregoing procedure is repeated, beginning with the entry of the right-hand "1" into the mask. (678).

If the bit total is 36 and the mask is incomplete, additional mask words are constructed using the foregoing procedure beginning with the zeroing of the mask and the NB storage locations. (680-683).

Following the POLRDF command of FIG. 1A is the first of two POLRDF commands. As with the POLRDF command,

each POLRDD command is assembled from a macrosequence to produce a call to an associated subroutine. FIG. 4A shows the macrosequence for the polynomial P with two arguments P and FORMAT, represented by information signals correspondingly designated "storage" locations in FIG. 1C. The contents of storage location P indicate the beginning buffer storage position of the heading for the associated polynomial P. Similarly, location Q indicates the beginning of the heading for polynomial Q. Storage location FORMAT marks the beginning of the format statement.

The processing operations accomplished by the POLRDD subroutine are summarized in the flow chart of FIG. 4B. As before, the reference numbers included in parentheses refer to the detailed coding included in Appendix I.

For each polynomial, the POLRDD routine (1) allocates storage for a heading in the lower portion of the data buffer, (2) fills the heading with signals which, inter alia, designate a location in the upper portion of the data buffer and (3) enters coefficient and exponent signals in the upper portion of the data buffer beginning at the designated location.

Allocation of heading storage is made by updating the heading address at the internal location C of the POLBEG subroutine shown in FIGS. 1C and 4C. The contents of the internal location C are designated *C, and refer to locations in the data buffer as shown in FIG. 4C. Initially, the internal location C indicates the lower bound of the data buffer, i.e., *C=*D. The updating depends on the number of words assigned to each heading.

In the example under consideration, each heading includes (1) the beginning address of the associated coefficient and exponent signals (2) the format address of the polynomial and (3) the number of terms in the polynomial.

Once the heading has been filled, coefficient and exponent signals are read and packed according to the format statement, beginning at the buffer storage location *B given by the internal storage location B of the POLBEG subroutine. Initially the internal location B specifies the upper bound of the data buffer as the beginning point for the storage of coefficient and exponent signals, i.e., *B=*A.

In the example under consideration, the polynomial P consists of three terms with one coefficient word and one exponent word per term. In general there will be more than one exponent word per term, depending upon exponent size.

More specifically, with reference to the flow chart of FIG. 4B, the POLRDD routine begins by zeroing an internal subroutine storage location HA, for Heading Address shown in FIG. 1C. (718).

This is followed by a test of the contents of location P of FIG. 1C. (39-43). The test is generated as a result of the assembly of a POLHDA macro, for Polynomial Heading Address. (719).

If the contents of location P are nonzero, a transfer is made which is of no consequence to the present processing. (44). If the contents are zero, a further test is made to determine if there is available space for the heading in the data buffer. (192-197). This is accomplished by a transfer within the POLHDA macro to a RFNCRH routine, for Rational Function Created Heading (171 and 47). The RFNCRH routine, in turn, contains a call (176) to a POLBSS macro (27-36) for Polynomial Buffer Storage Search, which contains a transfer (28) to POLBSS subroutine. (192-197). The latter does the actual test of the data buffer to determine if there is sufficient space.

In determining if there is sufficient space, the POLBSS routine provides for subtracting the contents of location C from the contents of location B, in FIG. 1C, (192-195). If the result is negative or zero, adequate space is indicated and a return is made to the RFNCRH subroutine. (196-197 and 177). Initially the data buffer is empty so that a return is assured. A similar condition prevails when the data buffer is only partly occupied. After extensive processing, however, the buffer space indicated as available may become inadequate, in which case an attempt is made to clear space by a subroutine which

is considered subsequently. (211-317). Upon return from the clearing subroutine a further test is made for heading space. (202-209). If insufficient space is indicated, there is a return to that effect to the calling sequence of the POLBSS subroutine. (32).

When there is sufficient space in the data buffer, a heading is created and its address stored in the reference location of FIG. 1C reserved for the polynomial P. This is accomplished by the RFNCRH subroutine which, in addition, updates the contents of location C containing the last available heading address. (177-182). The heading address thus established is stored for later reference at the internal location HA of the POLRDD subroutine as shown in FIG. 1C. (720).

Next, the heading is filled with three items of information, as shown in FIG. 4C. The uppermost word of the heading contains the next available address in the upper portion of the data buffer, given by the contents of internal storage location B of the POLBEG subroutine. (721-723). This word indicates the beginning position for the entry of coefficient and exponent signals associated with the polynomial under consideration. The second word of the heading is filled with the format address of the polynomial. (724-725). The format address designates the beginning position of the format statement shown in the main program portion of FIG. 1C.

The third word of the heading is reserved for the number of terms in the polynomial. The information to be entered here is accumulated during the processing of the POLRDD subroutine. For this purpose the subroutine contains an internal counting location W, shown in the POLRDD section of FIG. 1C, which is initially set to 1. (727-730).

The POLRDD subroutine also generates reference signals which are used in converting exponent signals according to the stored format statement of FIG. 3D. For the format statement shown there, each variable name is followed by an indication of the maximum number of bits contained in the associated exponent. Consequently the number of bits in a particular variable can be determined with respect to a reference parameter which is double the number of variables in the polynomial. For this purpose an indication of double the number of variables is obtained from the second word of the format statement by a single bit shift of the word contained there and the resultant is stored at internal location 2V of the POLRDD subroutine. (731-733). In addition, the conversion of exponent signals is expedited by a reference to the lowermost, or mask location of the format statement of FIG. 3D. The latter is stored at internal location BIT. (734-736).

The next operation is to read an input card containing information about the polynomial P. In the present embodiment there is a separate card for each term, which is in the form of a coefficient followed by a blank, followed by comma-delimited numbers, indicating the values of the exponents assigned to the successive variables. For example, if the polynomial P is $X+Y$ and the polynomial Q is $2X^2+3XY+Z$, the manipulation of this polynomial information requires at least three variables so that in accordance with the invention, the polynomials are represented

$$P=1X^0Y^1Z^0+1X^1Y^0Z^0$$

$$Q=2X^2Y^0Z^0+3XY^1Z^0+X^0Y^0Z^1$$

which respectively appear on successive data cards as

1 0, 1, 0
1 1, 0, 0
0
65 and
2 2, 0, 0
3 1, 1, 0
1 0, 0, 1
0

70 with the terminal zero of each set marking the end of the preceding polynomial.

The reading of a card begins with the initialization of a system subroutine, after which the information contained in the first card is entered into the multiplier-quotient register.

(740-748). The first word is a coefficient which is stored at the internal subroutine storage location COEFF of FIG. 1C. (749). The coefficient is next tested to determine whether it is zero, indicating the end of the term, in which case a transfer takes place to the POLCFM operational sequence, discussed in more detail subsequently. (750-751). If the coefficient is nonzero, the POLBSS routine is called to determine if there is sufficient space. (752). If sufficient space is indicated, the coefficient is stored at the location specified by the B pointer. (753-758).

In the example under consideration, the coefficient of the first term is unity, which is entered, as shown in FIG. 4C at the location $*A$ given by the first word of the heading address, which is itself at location $*C = *D - 3$.

After the coefficient is entered, preparation is made for entering one or more exponent words. This entails setting the three index registers used in the POLRDF routine to count variables, bits and words. (761-763).

Exponent information is read into the multiplier-quotient register, after which it is stored at the internal location EXP, for Exponent. (764-765). The number of bits in an exponent word is obtained from the format statement of FIG. 3D and stored at various locations of the processing sequence. (766-770). A "1" is set in the accumulator and shifted according to the number of bits indicated for the variable under consideration. (771-772). Thus shifted, the contents of the accumulator are used to test the internal location EXP to verify that no overflow has taken place in which case the exponent word is stored at the next available location in the upper portion of the data buffer. (773-780).

As long as the count of the maximum number of bits in the exponents that have been stored is less than 36, the foregoing procedure is repeated for succeeding variables. (782-783 and 788). When the bit count attains 36, the next available location in the upper portion of the data buffer is incremented and the earlier procedure repeated.

In the present example, the exponent information of the first term of polynomial P is 0,1,0. This information is packed into a single exponent word at location $*A+1$ of FIG. 4C.

When all of the exponent words of a term have been stored in the data buffer the data buffer location containing the number of terms is incremented and the foregoing procedure is repeated until all of the coefficients and exponents associated with a polynomial expression have been entered into the data buffer. (790-794). At that time a terminal zero is encountered and the POLCFM, for Polynomial Canonical Form, subroutine, is called into operation. (751).

The POLCFM subroutine inspects the exponent signals stored in the upper portion of the data buffer. If the polynomial is in canonical form, the exponents are in lexicographic order, in which each exponent word is ordered according to its numerical value. Continuing the earlier example, of the polynomial P , the exponent words are 0,1,0 and 1,0,0. Taken without the delimiting commas, the exponent words can be treated as the numbers 010 and 100 respectively. Thus they are initially in the lexicographic order prescribed by the invention. However, the exponent words in the upper portion of the data buffer for the three term polynomial Q are in the order

2,0,0
1,1,0
0,0,1

and are, hence, in a descending sequence instead of the desired ascending sequence.

The exponent words of the polynomial Q are reordered by the operations summarized in the POLCFM flow chart of FIG. 4D. As a result they ultimately appear in the data buffer in the order shown in FIG. 4C.

The POLCFM subroutine is initialized by storing the heading address of the polynomial at an internal subroutine storage location and by deriving arguments for the subroutine which indicate (1) the polynomial data address in the upper portion of the data buffer and (2) the number of terms in the polynomial. (902-907).

Next the heading is tested to determine whether it applies to a polynomial or to a constant. (909). The actual test is accomplished by a transfer to an RFNHDT subroutine, for Rational Function Heading Test. (832-848). In the case of a constant, the first word of the heading contains a code number 5, and the second word contains the value of the constant. If the first word of the heading is zero, an idle heading is indicated. Other code numbers are assigned to signify various classes of polynomial functions.

Once the heading has been tested, additional initialization is made of internal subroutine storage locations for indicating the number of terms in the polynomial, the number of words per term, and the number of exponent words. (917-920). If the number of terms is one or zero, reordering is unnecessary, and a transfer is indicated. (922-925). Otherwise the polynomial contains more than one term and various internal locations of the subroutine are set with the number of exponent words per term. (928-938).

This is followed by the establishment of a sorting index k which is initially set to 1. (940-941). The sorting index is necessary since the number of exponent words per term may exceed unity, in which case sorting begins on a block basis and then proceeds to a subblock basis.

The actual sorting takes place by a transfer to a SORT subroutine (942). The latter establishes the block to be sorted, which initially is taken as the entire polynomial information. (1057-1060). Since coefficient signals precede the exponent signals in the data buffer, the two are interchanged, and sorting takes place with a standard system sorting routine, following which the original coefficient-exponent relationship is restored. (1062-1089).

After the first block has been sorted, the number of coefficient words E is tested against the sorting index k . (1090-1094). If the number of coefficient words exceeds the sorting index, it is necessary to sort on a subblock basis until the last subblock has been sorted. (1095-1148).

When the sorting operation is completed, terms with like sets of exponent signals are combined and consolidated by a return to the main POLCFM subroutine. The terms are compared on the basis of indices I and J which are set in respective index registers. (946-961). The exponent of term I is compared with the exponent of term J. (980-984). Initially, the indices I and J refer to the same term. If the exponents are equal, term I is combined with term J. (1005-1009). If the resulting term is nonzero the index I is incremented and the earlier procedure repeated; if it is zero, the index J is decremented and the earlier procedure repeated. (1010-1012).

If the compared terms are unequal, the index J is incremented. (989). If there had been an earlier finding of equality, term I is moved to the position of term J. (990-998). After all terms have been tested, the parameter N, indicating the number of terms, is adjusted if there had been an earlier finding of equality. (999 and 1015-1028). When the terms of the two polynomials have been consolidated, a final test is made to determine if the resulting polynomial is a constant. (1031-1033).

Once signals representing polynomials P and Q have been entered into the data buffer, the machine is ready to undertake polynomial multiplication in accordance with the POLMPY operation of FIG. 1A.

As with the other operations specified in FIG. 1A, the command POLMPY constitutes a macrocall, shown in FIG. 5A, to a subroutine of the same name. The subroutine has three arguments R , P and Q , of which P and Q represent the polynomials to be multiplied and R represents the resulting product. In the execution of POLMPY, the longer of two polynomials is multiplied by each term of the shorter, using POLOMP, for Polynomial One Term Multiply, to produce partial products. The resulting partial products are then accumulated using POLADD, for Polynomial Add.

Assuming that polynomial P has np terms and that polynomial Q has nq terms, with $np \leq nq$, a "leapfrog" method is used if there is sufficient space available in the data buffer. This method allocates $np+1$ blocks, each of length nq .

The first partial product is placed in the NP-th block and the second partial product is placed in the NP+1st block. At this point a transfer is made to the POLADD subroutine to produce a partial sum at the beginning of the NP-1st block. The next partial product is placed in the NP+1st block, and the next partial sum is started at the beginning of the NP-2nd block. The foregoing procedure is repeated until the final result appears at the beginning of the first block.

If the I-th partial product is $T_i = P_i Q$ and the I-th partial sum is

$$PS_i = \sum_{j=0}^i T_j;$$

Then the final result which begins at the first reserved block and extends no further than NP blocks is

$$PS_{NP} = \sum_{j=1}^{NP} T_j$$

The foregoing technique is illustrated in FIG. 5B for the example under consideration. The polynomial P is stored in the upper portion of the data buffer as a sequence of two terms Y and X , it being understood that this is a shorthand notation for the actual storage shown in FIG. 4D for which two data words are required, for each term.

Since the polynomials P and Q have two and three terms, respectively, the previously considered inequality between NP and NQ is satisfied. Where the inequality is not satisfied, the polynomial headings are interchanged.

For the polynomials being considered, reservation is made in storage of three blocks of three terms each. The first, or zero order, partial product is given by multiplying the polynomial Q by the first or zero order term of P , $P_0=Y$, with the result that $P_0 Q = YZ + 3XY^2 + 2X^2Y$ which is entered into the NP-th or second reserved block of the data buffer. The zero order partial product T_0 is also the zero order partial sum PS_0 . The partial product of the polynomial Q multiplied by the second or first order term of P , $P_1=X$, gives the result $P_1 Q = XZ + 3X^2Y + 2X^3$ which is entered into the NP+1st or third reserved block of the buffer.

Next the partial products are combined into a partial sum $PS_1 = P_0 Q + P_1 Q = YZ + XZ + 3XY^2 + 5X^2Y + 2X^3$ which is placed at the beginning of the NP-1st block and partially overwrites the NP-th block. Since NP has been taken as 2, the partial sum PS_1 is the final sum and commences at the head of the first reserved block.

In carrying out the foregoing procedure, the operations of the POLMPY subroutine are summarized in the flow chart of FIG. 5C and shown in greater detail in the flow charts of FIGS. 5D-1 through 5D-3. The parenthesized numbers refer to detailed operations, which, as indicated by the Roman numeral following each set of parentheses, are included in Appendix II.

Turning to FIG. 5D-1, the subroutine begins with the initialization of selected internal storage locations. (1324-1330)II. This includes (1) the zeroing of locations PS and TI , which are used for the heading addresses of the partial sum and the latest partial product (2). The heading of the internal reference locations of the polynomials P and Q (3) and the zeroing of reference location R for the result.

Next a heading is created for the resulting polynomial R using the operations of the POLHDA macro discussed earlier in conjunction with the POLRDD operations, after which the heading address is stored at the internal reference location R . (1331-1332)II.

Subsequently, the headings of the polynomials P and Q are tested using the RFNHDT subroutine discussed in conjunction with POLCFM. (1346 and 1356)II. The numbers of terms in the polynomials P and Q are stored in locations NP and NQ respectively. If the headings indicate constant terms, transfers are made accordingly. (1352 and 1362)II.

If both P and Q are nonconstant polynomials, their terms are compared. (1364-1365)II. The processing is arranged for the number of terms in the polynomial P to be less than or equal to the number of terms in Q . Should this condition not prevail, the headings and reference locations of the two polynomials are interchanged. (1368-1379)II.

In addition the polynomials must be of the same format. This is verified and the format address stored at the internal location FA. (1381-1391)II.

Once the polynomials are found to have the same format, they are ready to be multiplied. This, in turn, depends upon the number of terms in the multiplier, which is tested. (1415-1417)II. If the multiplier is a monomial, the multiplication can be made directly by the POLOMP subroutine. Otherwise, a determination of the data buffer space needed for the fast, "leapfrog" method is made. (1418-1427)II.

The space that is needed is checked by the POLBSS subroutine, for Polynomial Buffer Storage Search, in the fashion that has been considered previously in conjunction with the flow chart of FIG. 4D for the POLRDD subroutine. (1428)II and (192-197). If the available space is indicated to be inadequate, an attempt is made with the POLBSS subroutine to consolidate the stored data items. (211-317).

During the course of processing headings in the lower portion of the data buffer are created which designate data addresses for blocks of coefficient and exponent words in the upper portion of the buffer. The headings are discarded or rendered inactive when no longer needed, but, to expedite processing, their associated data items are allowed to remain in the upper portion of the buffer as long as the remainder of the buffer provides adequate storage.

When a need arises for additional storage, the current headings are examined to establish that their indicated data addresses correspond to a succession of minimum possible addresses. The minimum possible addresses begin with the upper bound of the data buffer. If the data addresses of all headings exceed the minimum possible address, the data items associated with the minimum actual address are moved to the minimum possible address and the associated heading changed accordingly. Subsequently the minimum possible address is updated by the extent of the block required by the data items that have been moved, and the foregoing procedure is repeated for the remainder of the current headings until all of the data entries occupy contiguous blocks in the upper portion of the data buffer.

The procedure for consolidating the data items in the upper portion of the buffer is given in greater detail by the flow chart of FIG. 5D-2. After initialization, the pointer to the inner bound of the data buffer is set with the upper bound location $*A$, which is in turn stored at an internal subroutine location NAAPRE, for Next Available Previous Address, which is the minimum possible data address. (214-224).

Then, to allow examination of the data addresses of the headings in turn, the space occupied by all of the headings is established and a corresponding indication is set in Index Register 1. (225-233). The latest heading, i.e., the last one entered into the data buffer (at location $*C$ of FIG. 1C), is considered first. Its included data address is compared with the minimum possible address contained in internal location NAAPRE. (237).

If the address given by the present heading is less than the minimum possible address, it cannot be the one being sought, and a transfer is made to allow consideration of other headings. (240). If the addresses being compared are equal, or if the address given by the heading is greater than the minimum possible address, a further comparison is made. (239).

For the latest, i.e., first, heading the second comparison is made with the address of a more remote heading. For subsequent headings the comparison takes place with the data address given by a previously considered heading. If the compared addresses are equal, an error is indicated. (241). If the present address exceeds the previous address, a transfer is

made to allow consideration of other headings. (240). The final condition for the second comparison is for the comparing address to be smaller than the compared address. For the first heading the final condition prevails when the indicated data address is smaller than the remote heading address. For subsequent headings the final condition is satisfied when the present heading address is smaller than the previous heading address. In either case, the comparison address is stored at internal location SUP, for Superseded Data Address. (243).

The foregoing procedure is repeated (244) until all headings have been examined, at which point the internal location SUP contains the minimum actual address.

If no heading with a minimum address is found, a return is made to the main subroutine. (245-248). Otherwise the heading is identified with the minimum address and stored at an internal location HA, for Heading Address. (249-251). This is followed by an updating of the minimum possible address by the extent of the data of the minimum actual address. (254-271). If the minimum actual address does not correspond to the earlier minimum possible address, given by the inner bound pointer, the data are moved accordingly, after which the inner bound pointer and the heading are updated and the earlier procedure repeated. (274-291). When all data items have been packed in contiguous blocks in the upper portion of the data buffer, a return is made to the main POLMPY routine of FIG. 5C. (297).

If there is adequate space for the leapfrog method, an indication to that effect is entered at an internal location LSW, for Leapfrog Switch. (1429)II. Otherwise an overwrite method of multiplication is used.

When the leapfrog method is used, subroutine reference locations to the data buffer are filled. (1432-1437)II. These references locations are DATI, for the temporary data address of the latest partial product; and DAPS, for the data address of the partial sum.

The initial data address of the partial sum is for the zero order term PS_0 at the beginning of the NP-th block, which is also the data address of the zero order partial sum T_0 (See FIG. 5B). The initial data address of the partial product location is for the first order term T_1 at the beginning of the NP+1st block (See FIG. 5B).

The next step is to multiply the terms of polynomial Q by the first term P_0 of the polynomial P . (1440-1445). The operations encompassed by this step are outlined in the flow chart of FIG. 5D-3. As a preliminary, provision is made for identifying the individual terms P_i of the multiplier polynomial. For this purpose the POLMPY subroutine includes a heading at location PI for the I-th term of polynomial P (See FIG. 1C). The data address of heading PI is set initially with the upper address of the data buffer. (1440-1441)II. Index register 1 is set with the number of terms in the polynomial P . (1442)II. Initialization is followed by a transfer to a POLOMP subroutine, for Polynomial One Term Multiplication. (1443)II. The latter subroutine creates a heading for the partial sum PS , using the POLHDA macro discussed in conjunction with the POLRDD COMMAND. (856)II.

At this point, the reference address, given by location C of FIG. 1C, is stored so that subsequently created headings will be only temporary. (859)II. Next there is a transfer to the POLDUP subroutine, for Polynomial Duplication. (860)II. This subroutine duplicates the polynomial Q starting at the first available address in the upper portion of the data buffer, as shown in FIG. 5B. A duplicate is made in order that the multiplication of the polynomial Q may take place on a term by term basis at the duplicate locations without disturbance to the original polynomial at the location specified by the heading.

The POLDUP subroutine initializes its internal storage locations and generates a temporary heading in the lower portion of the data buffer which designates the first available address in the upper portion of the buffer. (447-451). Once the number of words of storage required for the polynomial has been established, the polynomial Q is copied into the data

buffer beginning at the location indicated by the newly created temporary heading and the pointer at location B is updated accordingly. (460-489).

The call to the POLDUP subroutine from the POLOMP subroutine is followed by a call to a POLOMO subroutine, for Polynomial One Term Multiply and Overwrite. (861)II. This is the subroutine which accomplishes the actual term by term multiplication and substitutes for each pair of multiplied terms the result of the multiplication beginning at the upper buffer storage locations specified by the temporary heading.

In essence the POLOMO subroutine multiplies the coefficient of a selected term of the polynomial P by each term of the polynomial Q and stores the result. (769-771)II. The multiplication is followed by an addition of the exponent words of the multiplied terms of the polynomials P and Q . (788-790)II. The exponent words thus added are checked to determine whether or not overflow has taken place from one mask position to another. (791-793)II. If there has been no overflow, the resultant exponent word or words are stored in the data buffer following the result of the coefficient multiplication. (795)II.

Considered in greater detail, the POLOMO subroutine begins by storing the headings of the duplicated polynomial Q and the single term of the multiplier polynomial P at internal locations of the subroutine. (708-711)II. The headings are tested, as in the case of the POLMPY, to determine if either pertains to a constant. (712-731)II. Testing is followed by calculations of (1) the words per term and the total words in

25 the polynomial Q ; (2) the format address of the polynomial Q ; and, (3) the mask address as supplemented by the number of exponent words per term. (732-746)II. The latter quantity is used in checking the exponent addition and is calculated using the POLFMI subroutine, for Polynomial Format Information. (871-891). In addition, successive coefficients of the polynomial P are extracted and stored at internal subroutine locations. (748-751)II. Index registers 1 and 4 are set with the total number of words in polynomial Q and the data address of the polynomial, as supplemented by the total number of words, is stored at reference locations of the subroutine. (762-768)II.

30 The initialization of the POLOMO subroutine is followed by a so-called I loop which is used for coefficient multiplication. (769-804)II. The I loop contains a nested J loop which is used for exponent addition. (788-799)II. The J loop contains test operations for determining (1) if all of the terms of polynomial Q have been processed and (2) a test of whether all of the exponent additions have been made for each term of the polynomial Q . (797-803).

35 The testing of exponent addition for overflow is spaced by being expressed in terms of sense indicator operations. However, the testing for overflow is more readily understood in terms of the basic Exclusive-OR and AND operations that are performable in the accumulator. If the exponent word of the multiplier term is at storage location X , and the term by which it is being multiplied is at storage location Y , the exponent checking operation takes the form of the expansion shown in FIG. 5E-1, which is applicable to the apparatus block diagram 40 shown in FIG. 5E-2, as well as the data processing machine by which the invention is being illustrated.

45 The apparatus block diagram of FIG. 5E-2 includes a memory 52-1, a storage register 52-2, an adder 52-3, an Exclusive-OR network 52-4, an AND network 52-5 and an accumulator register 52-6. In addition, the apparatus includes 50 memory address and instruction decoder circuitry 52-7 which operates in conventional fashion to control the memory 52-1, as well as gating (not shown) among other components 52-1 through 52-6.

55 The apparatus block diagram of FIG. 5E-2 includes a memory 52-1, a storage register 52-2, an adder 52-3, an Exclusive-OR network 52-4, an AND network 52-5 and an accumulator register 52-6. In addition, the apparatus includes 60 memory address and instruction decoder circuitry 52-7 which operates in conventional fashion to control the memory 52-1, as well as gating (not shown) among other components 52-1 through 52-6.

65 The first three instructions of the listing in FIG. 5E-1 at reference Nos. 50-1 through 50-3 are responsible for adding the contents at storage location X of the memory 52-1 to the contents at storage location Y and storing the resultant summation at storage location Z . In addition, the accumulator register 52-6 also contains the resultant summation. Hence, the 70

instruction at reference No. 50-4 brings about an Exclusive-ORing between the contents of storage location X and the summation in the register 52-6, through the use of the Exclusive-OR network 52-4. This is followed by an Exclusive-ORing, as directed by the instruction at reference No. 50-5 with the contents at storage location Y . The outcome of this operation is ANDed, by the instruction at reference No. 50-6, with the contents at a mask location of the storage means, through the AND network 52-5. The first EXCLUSIVE-ORing operation has the effect of eliminating any contribution to the initial summation that did not involve a carry, made by the contents of location X . Similarly, the second EXCLUSIVE-ORing operation eliminates any contribution from the contents of Y which did not involve a carry. As a result, any signals remaining must have resulted from carries. A test of any carries in preassigned positions of the mask is made by the final ANDing operation. In the illustrative example, the contents of location X , for the first term of the polynomial Q are 000000000001₈. The similar contents of location Y for the first term of the polynomial P are 00000000100₈. The summation of these two contents produces a machine word at location Z in the form 00000000101₈. The first EXCLUSIVE-ORing operation eliminates the information from storage location X so that the result is 000000000001₈. The second EXCLUSIVE-ORing operation eliminates the contribution from location Y so that the result is 000000000000₈. This resultant contains no carries so that the ANDing operation has no effect on it. However, if the contents of locations X and Y had each been given by nine binary signals, respectively represented as 053₈ and 046₈, an overflow carry would have been indicated using the illustrative mask. The resulting summation would have been 121₈. The latter is converted into 134₈, which has a binary representation of 001011100₂, after the two indicated EXCLUSIVE-ORing operations. Hence, starting from the right-hand digit, carries are indicated for the third, fourth, fifth and seventh digit positions. The corresponding binary represented portion of the mask is 001000001₂, so that the final ANDing operation yields 00100000₂, for which an overflow carry is indicated for the seventh digit position.

Upon completion of the operations of the POLOMO subroutine there is a return to the POLOMP subroutine which indicates a transfer to an RFNDPH subroutine, for Rational Function Duplicate and Place Heading. (862)II. The RFNDPH subroutine transfers the overwritten term by term multiplication at the upper data buffer location indicated by the temporary heading to the position within the data buffer assigned to the zero order partial sum whose heading is at location *D-12 as shown in FIG. 5B. The operations of the RFNDPH subroutine by which this is accomplished amount to a direct interchange of information between the respectively

indicated locations. (852-867)II. The restoration of the internal reference location C completes the POLOMP subroutine. (863-864)II.

The next step of the main POLMPY subroutine is a test of the POLMPY subroutine location LSW and the setting of the contents of location B with the contents of internal subroutine location DATI, in preparation for the entry of the multiplication of the second term of the polynomial P by the polynomial Q . (1448-1450)II. The contents of location DATI specify the beginning of the term of the NP+1st block of the data buffer, as shown in FIG. 5B. The information for this block is obtained using the POLOMP subroutine just considered. (1456)II.

At this point the data buffer contains two partial products which are combined (1462-1468)II into a partial sum. The partial sum is brought about using a POLADD subroutine, for Polynomial Addition.

Since the terms of the polynomials P and Q are in canonical form, the data blocks containing their partial products are also in canonical form. Thus each partial sum of two partial products is produced by comparing the exponents of the terms in each block and canceling them or merging them, beginning at the data address that has been set for the partial sum. (1037-1060)II. If the exponents of corresponding terms are equal, the coefficients are added. (1063-1074)II. The initialization of the POLADD subroutine is similar to that of the previously considered POLMPY subroutine. (896-1036)II. The entry of the partial sum into the data buffer is followed by operations which restore the original subroutine and include the filling in of the heading of the resultant partial sum. (1157-1164)II.

The foregoing generation of partial products and their combination into partial sums is continued in the POLMPY subroutine until the data items of the polynomials P and Q are exhausted. (1470-1471)II. For the example under consideration, the polynomial P has two terms and the desired result appears after one application of the POLADD subroutine.

Once the result of the desired calculation is available in storage, all that remains is the extraction of that information from storage. This is accomplished by the POLPRT command of FIG. 1A. (1315-1567). This command produces a call to a subroutine of the same name, by which each term of the polynomial is printed on a single line with continuation lines used where necessary. In the case of the IBM 7090 all coefficients are right adjusted so that they form a column in the output. The exponents typically form additional columns headed by their corresponding variable names. In each line the coefficient is separated from the exponent by two blanks and the exponents are separated from each other by single blanks.

Other adaptations of the invention still occur to those skilled in the art.

***** REMOTE PROGRAM CALLED BY END *****

LITERALS

04426 IS THE FIRST LOCATION NOT USED BY THIS PROGRAM

NO ERROR IN ABOVE ASSEMBLY

What is claimed is:

1. The machine method of processing information constituted of at least one variable and associated parameters, which comprises the steps of
  1. generating signals designating a first set of locations in a machine memory and storing the signals thus generated at a second set of locations identified with said information,
  2. generating signals designating a third set of locations in said memory and storing the signals thus generated at the memory location of said first set,
  3. generating signals representing the parameters of one variable and storing the signals thus generated at the memory location of said third set, and
  4. generating format signals indicating the format of the signals generated at step (3) and the name of the variable associated with said variable and storing said format signals at a fourth set of memory locations.
2. The method as defined in claim 1 wherein the signals generated by step (2) further designate locations of said memory for the format of said variable.
3. A programmed data processing machine method of processing information constituted of at least one variable and associated parameters, which comprises the steps of
  1. generating data signals representing said parameters associated with each variable and storing the signals in a machine memory,
  2. generating and storing heading signals designating the location of signals generated by step (1),
  3. generating and storing identification signals designating the location of the signals generated by step (2), and
  4. generating and storing format signals for each of the signals generated at step (1).
4. The machine method of processing information which comprises the steps of
  1. generating signals indicating a fixed lower bound of a set of storage locations in a machine memory,
  2. generating signals indicating a fixed upper bound of said set of storage locations,
  3. generating signals indicating a variable lower bound with respect to the bound of step (1),
  4. generating signals indicating a variable upper bound with respect to the bound of step (2),
  5. entering signals referring to the bound of step (4) into the location indicated by the bound of step (3), and
  6. updating the bound of step (3) by the extent of the signals stored according to step (5).
5. The stored-program-controlled machine method of processing polynomial information constituted of at least one term of coefficient and exponent signals, which comprises the steps of
  1. testing the coefficient signals of one term for the termination thereof,
  2. storing the signals of the coefficient of said term at a first word location of a machine memory,
  3. storing the signals of a first exponent of said term at a new location of said memory bearing a fixed relation to said first location,
  4. packing said new location with signals of succeeding exponents to the extent that said new location does not overflow, and
  5. repeating steps (3) and (4) with successive new locations each bearing a fixed relation to said first location, and

with the next exponent not having its signals packed replacing said first exponent upon packing the previous new location to the point of imminent overflow, until all signals of a term have been stored.

6. The machine method of processing polynomial information constituted of exponent signals stored in a plurality of word locations of a memory, which comprises the steps of
  1. ordering the exponent signals in said word locations according to the numerical magnitudes corresponding to the signals of each word, and
  2. combining, for the signals thus ordered, all successive words representing like numerical magnitudes.
7. The machine method of multiplying together two polynomials, which comprises the steps of
  1. generating signals representing a first-order partial product of the first term of one polynomial by all the terms of the other polynomial and storing the resultant signals at a first block of machine storage locations,
  2. generating signals representing a higher order partial product of another term of said one polynomial by all the terms of said other polynomial and storing the resulting signals at a successive block of machine storage locations,
  3. generating signals representing a summation of the results of steps (1) and (2) and storing the result of said summation at a block of machine storage locations preceding and partially overwriting those of step (2), and
  4. repeating steps (2) and (3) and, for each repetition, storing the resultant summation signals at a block of storage locations preceding and partially overwriting those of each earlier repetition.
8. Apparatus comprising means for storing (1) a first set of signals indicative of the packing of signals representing a plurality of distinctive quantities into groups of preassigned extent and (2) second and third sets of signals packed according to the signals of said first set,

register means,

means for adding the signals of said second and third sets to each other to form a sum signal, means for loading said sum signal into said register means,
- 40 means for performing an EXCLUSIVE-OR operation between the contents of said register means and the signals of said second set to form a first EXCLUSIVE-OR result signal, means for storing said first EXCLUSIVE-OR result signal in said register means, means for performing an EXCLUSIVE-OR operation between said first EXCLUSIVE-OR result signal and the signals of said third set to form a second EXCLUSIVE-OR result signal, means for storing said second EXCLUSIVE-OR result signal in said register means, and means for performing an AND operation between the contents of said register means and the signals of said first set.
- 45 9. Apparatus comprising

means for adding first and second sets of digit signals, together with their carries, to form a third set of signals occupying preassigned digit positions;

means for subtracting, without carries, (1) the signals of the first set from those of said third set to form a first residual set of signals and (2) the signals of the second set from those of said first residual set to form a second residual set; and

means for testing the signals of said second residual set for a carry signal in one of said preassigned digit positions.
